UNITED STATES PATENT OFFICE.

WILLIAM E. HAWKINS, OF AMITYVILLE, NEW YORK.

SOCKET-SHELL FOR INCANDESCENT ELECTRIC LAMPS.

1,383,626.

Specification of Letters Patent.

Patented July 5, 1921.

Application filed September 27, 1920. Serial No. 413,075.

To all whom it may concern:

Be it known that I, WILLIAM E. HAWKINS, a citizen of the United States, residing at Amityville, in the county of Suffolk and State of New York, have invented a new and useful Improvement in Socket-Shells for Incandescent Electric Lamps; and I do hereby declare the following, when taken in connection with the accompanying drawings and the characters of reference marked thereon, to be a full, clear, and exact description of the same, and which said drawings constitute part of this application, and represent a view, partly in side elevation and partly in vertical central section, of a socket-shell embodying my invention.

My invention relates to an improved socket-shell for incandescent electric lamps, the object being to facilitate the application of shade-holders thereto and to avoid the mutilation of the threads of the shells and shade-holders as well as the deformation of the latter resulting from the strains imposed upon them in attempting to screw them upon the shells when a false start has been made.

With these ends in view my invention consists in a socket-shell having certain details of construction as will be hereinafter described and pointed out in the claim.

In carrying out my invention as herein shown, the socket-shell consists of a domical cap 2 and a cylindrical shell-body of which the upper portion 3 is larger in diameter than its lower portion 4, the said portions 3 and 4 being separated by a shoulder 5. The lower and smaller portion 4 of the shell-body is formed with a circumferential abutment-bead 6, with the threads 7 located below the same, and with inwardly turned lead-flange 8 located directly below the said threads and constituting the lower edge of the shell-body. When a shade-holder of any standard form is applied to a socket-shell as thus construct-

ed, the lead flange 8 effects the lining up of the threads of the shade-holder with respect 45 to the threads 7 of the socket-shell in such a way as to prevent the holder from being tilted and a false start made, whereby the threads of the socket-shell and of the shade-holder are prevented from being mutilated 50 and the shade-holder prevented from being bent, and whereby also time is saved. It is a common experience with fixtures of this class that unless the greatest care is taken in applying a shade-holder to a socket-shell it 55 is applied thereto out of line therewith and the shade-holder then makes a false start which precludes the correct engagement of the threads of one part with the other. In such a case the shade-holder must be removed 60 and a new start made, often resulting in repeated trials before the shade-holder can be correctly applied to the socket-shell. These objections are overcome by my invention since the lead flange insures the correct application in the first instance of the holder 65 to the shell.

I claim:

A socket-shell for incandescent lamps, the said shell having its body formed near its 70 lower end with an abutment-bead, with screw threads located below the said bead and with an inwardly turned lead-flange located below and merging directly into the said screw threads and forming the extreme lower edge 75 of the shell-body, whereby a shade-holder applied to the said lead-flange has its threads lined up thereby with the threads of the body of the shell.

In testimony whereof I have signed this 80 specification in the presence of two subscribing witnesses.

WILLIAM E. HAWKINS.
